(57) **CLAIM**

The ornamental design for a pool cleaning brush, as shown
and described.

DESCRIPTION

FIG. 1 is a top plan view illustrating a pool cleaning brush
illustrating my new design;

FIG. 2 is a bottom plan view thereof;

FIG. 3 is a side elevational view taken from the top side of
FIG. 1;

FIG. 4 is an opposite side, taken from the bottom side of
FIG. 1; and,

FIG. 5 is an end elevational view, taken from the right side
of FIG. 1, it being understood that the left side is a mirror
image thereof.

The broken lines shown in the drawing views are for
illustrative purposes only and form no part of the claimed
design.
